UNITED STATES PATENT OFFICE

118,050

DESIGN FOR A SLIDER BODY FOR SLIDE FASTENERS

Birdsall P. Lawson, New York, N. Y., assignor to
Ideal Fastener Corporation, Brooklyn, N. Y., a
corporation of New York

Application April 26, 1939, Serial No. 84,559

Term of patent 3½ years

To all whom it may concern:

Be it known that I, Birdsall P. Lawson, a citizen of the United States and a resident of the county of Queens, city and State of New York, with a post-office address at No. 104-51 93rd Avenue, Richmond Hill, in the county of Queens, city and State of New York, have invented a new, original, and ornamental Design for a Slider Body for Slide Fasteners, of which the following is a specification, reference being had to the accompanying drawing, forming part thereof in which—

Figure 1 is a plan view of a slider body for slide fasteners, showing my design.

Figure 2 is a side elevation of the same.

Figure 3 is a rear elevation of the same.

Figure 4 is a front elevation of the same.

Figure 5 is a front elevation of the same in section, taken along lines 5—5 of Figure 1.

I claim:

The ornamental design for a slider body for slide fasteners, as shown.

BIRDSSL P. LAWSON.
